UNITED STATES PATENT OFFICE.

CHARLES D. ROSS, OF MILWAUKEE, WISCONSIN, ASSIGNOR OF ONE-HALF TO
LAKE SHORE STONE COMPANY, OF MILWAUKEE, WISCONSIN, A COR-
PORATION OF WISCONSIN.

APPARATUS FOR UNLOADING MARINE VESSELS.

No. 842,338.

Specification of Letters Patent.

Patented Jan. 29, 1907.

Application filed August 1, 1906. Serial No. 328,682.

To all whom it may concern:

Be it known that I, CHARLES D. Ross, a citizen of the United States, residing at Milwaukee, county of Milwaukee, and State of Wisconsin, have invented new and useful Improvements in Apparatus for Unloading Marine Vessels, of which the following is a specification.

My invention relates to improvements in apparatus for unloading crushed stone, coal, grain, and other similar substances from marine vessels and discharging such substances at a distance from the vessel in any suitable place of deposit therefor, and it pertains more especially to the construction and arrangement of the several conveyers and their supporting mechanism by which the substances to be unloaded are simultaneously conveyed from two parallel longitudinal hoppers located in the body of the vessel to a central conveyer preparatory to being elevated and discharged from the vessel.

The construction of my invention is explained by reference to the accompanying drawings, in which—

Figure 1 is a longitudinal section of a vessel provided with my improved apparatus. Fig. 2 is a transverse section drawn on line xx of Fig. 1. Fig. 3 is a detail representing a plan view of the front end of the several conveyers and their supporting mechanism. Fig. 4 is an end view of the device shown in Fig. 3. Fig. 5 is a detail representing one of the two transverse conveyers by which the material to be unloaded is conveyed from the side of the vessel to and discharged upon the central conveyer. Fig. 6 is a vertical section of one of the compartments, a conveyer and conveyer-supporting mechanism; and Fig. 7 is a detail showing the manner of supporting the rollers upon which the conveyer-belts are operated.

Like parts are identified by the same reference characters throughout the several views. 45 1 represents the body of an ordinary marine vessel, which is subdivided longitudinally into two compartments or so-called "hoppers" 2 by the central vertical partition 3, and said compartments are respectively 50 provided with downwardly-converging floors 4, upon which the crushed stone, coal, and other substances to be conveyed are deposited.

It will be understood that in practical use the compartments 2 are filled with the material to be handled by my apparatus. The converging floors 4 terminate at slight distances apart, leaving longitudinal apertures 5 between them, through which the contents of the vessel is adapted to be discharged upon the conveyers 6. For conveyers I preferably use a heavy rubber belt formed of several plies of canvas covered and interspersed with rubber, substantially like the ordinary rubber belting. These belts 6 extend longitudinally from one end of the respective hoppers 2 to the other beneath the discharge-apertures 5. The apertures 5 are closed by sliding gates 7, which are retained in place beneath the apertures 5 upon supporting-bearings 8. The gates 7 are preferably provided with apertures 9 near one side, whereby as they are drawn from the left toward the right (reference being had to Fig. 6) the contents of the hoppers 2 will be discharged through the aperture 9 upon the belts 6, when it will be carried forward by the revolving movement of said belt to the rear end of the vessel and discharge upon the transversely-arranged belts 10. When, 80 however, the gate is moved toward the left, as shown in Fig. 6, the apertures 5 will be closed and the escape of the contents thereby stopped. The upper portion of the endless belts comprising the conveyer 6 are carried by a plurality of sets of three each of rollers 11, 11 and 12, the rollers 11 being 85 preferably arranged at an angle to the horizontal, as shown in Fig. 6, while the central roller 12 is supported in a horizontal position, whereby the upper fold of said belt, upon which the contents of a vessel is carried and discharged, is retained in the trough-shape position, (shown in Fig. 6,) with its respective sides above its center. The lower 90 portion of the belt forming said conveyer is supported upon a plurality of sets of rollers 13, each set preferably comprising a plurality of rollers 14, as shown in Fig. 6. The rollers 11 are supported from the brackets 15 95 upon the upwardly-inclined trunnion 16, while the roller 12 is supported from said bracket upon the horizontal shaft 17. The rollers 13 are supported from the bracket 18 upon the shaft 19, and said brackets are supported from the horizontal timbers 20 and 100

21 of the hopper-supporting frame 22. The transversely-arranged belts 10 are respectively supported at the ends slightly below the upper fold of the longitudinal belts or conveyers 6, whereby the contents of the hoppers, which are carried forward on the upper fold of said belt, are discharged upon the upper fold of the endless belts 10, and is carried by said belts 10 to and discharged upon the longitudinal central belt 23 and from thence above the deck of the vessel and discharged upon the elevator-belt 24 of the conveyer 25. The conveyer 25 is of the ordinary construction and is pivotally supported from the deck of the vessel upon the turn-table 26 in the ordinary manner and is adapted to be swung upon either side of the vessel, as circumstances may require, for discharging the contents of the vessel. The belt 24 of the conveyer 25 is preferably operated by separate electric motor 27 through a train of gears 28 of ordinary construction, or the same may be operated by any other mode of power. The front end of the conveyer 25 is preferably suspended from the top of the tower 28 by ropes or cables 29 in the ordinary manner. The front end of said conveyer is adapted to be raised, lowered, and adjusted at any desired angle to the vertical upon either side of the vessel as circumstances may require. The transversely-arranged belts 10 are supported at their outer ends from the vessel by rollers 30, roller-supporting shaft 31, and, roller-supporting bracket 32, while their converging ends are supported from the vessel slightly above the upper fold of the belt 23 by the rollers 33, roller-supporting shaft 34, and shaft-supporting bracket 35.

40 Motion is communicated to the several longitudinal and transverse belts from the motive power (not shown) as follows: from the motor-shaft 36 to the longitudinal belts 6 6, through pinion 37, gear-wheel 38, wheel-supporting shaft 39, and pulleys 40 40, and from the shaft 39 to the two transverse belts 10 through the miter-gears 41 41 and 42 42, gear-supporting shaft 43 43, gears 44 44, pinions 45 45, pinion-supporting shaft 46 46, 50 and a plurality of belt-supporting pulleys 47 47, and motion is communicated from the shaft 43 to the central longitudinal belt 23 through the miter-gears 48 49, shaft 50, and pulley 51, whereby as the shaft 36 is driven by the motor all of said belts will be simultaneously operated, whereby the contents of the vessel will be discharged. It will be understood that the longitudinal compartments or hoppers are provided with a plurality of gates through which the contents are discharged, as previously stated, upon the upper fold of the longitudinal belts or conveyers 6. When desirous to discharge the contents of the vessel, the motor by which the several belts are operated being first started,

one or more of the gates 7 above the respective longitudinal belts 6 are opened, whereby the contents of the hoppers or compartments is gradually discharged upon the upper folds of the respective belts 6, when such contents is carried forward and deposited upon the respective transverse belts 10, by which it is conveyed to the longitudinal central belt 23 and from thence to the conveyer 25, as previously stated, by which conveyer it is conveyed to the proper place of deposit.

Heretofore it has been common in the construction of apparatus for the purposes described to employ elevator-buckets operating upon vertically-arranged endless belts for elevating the contents of a vessel from the bottom of the hold to the deck preparatory to discharging the same therefrom. One of the primary objects of my present invention is to give the elevating-belts such gradual inclines upwardly from the bottom of the vessel that the elevating-buckets may be dispensed with and the contents of the vessel conveyed upon the smooth surface of the belts. To accomplish this object, the front ends of the belts 6 90 are preferably inclined upwardly from beneath the hoppers above the upper surface of the transversely-arranged belts 10, and said transverse belts 10 are preferably inclined upwardly from their supporting-rollers 30 to 95 their supporting-rollers 33, when they discharge their contents at a higher level upon the upper folds of the belt 23, and a space is left between the front ends of the compartments 2 2 for said belt 23, whereby said belt 100 may be carried upwardly by a gradual incline from the transverse belts 10 to the conveyer 25 above the deck, the inclinations of the several belts being such that the contents of the vessel will be carried on their smooth 105 upper surface and the use of elevator-buckets is dispensed with.

Having thus described my invention, what I claim as new, and desire to secure by Letters Patent, is—

1. In a marine vessel of the class described the combination of two parallel compartments located upon the respective sides of the longitudinal center of the vessel, having downwardly-converging floors and discharge-apertures located at the apex of said floors, a conveyer located longitudinally beneath the discharge-apertures of each compartment, a third conveyer located centrally between and extending upwardly at an angle 115 to said first-named conveyers and two transversely-arranged conveyers communicating from the two first-named conveyers and adapted to discharge their contents upon said central conveyers, means for simultaneously operating all of said conveyers, and means for discharging the material elevated by said conveyers upon the respective sides of the vessel.

2. In a marine vessel of the class de- 130

scribed the combination of two parallel compartments one of the ends of which compartments are located at slight distances apart on the respective sides of the longitudinal center of the vessel leaving a longitudinal space between them for the reception of a central conveyer, said compartments having downwardly-converging floors provided with discharge-apertures located at their apex, doors for closing said passages, a conveyer located longitudinally beneath the passages of each compartment, a third conveyer located centrally of the vessel and extending upwardly at an angle to said first-named conveyers between the front ends of said compartments, and two transversely-arranged conveyers communicating between the two first-named conveyers with and adapted to discharge their contents upon said central conveyer, means for simultaneously operating all of said conveyers and means for discharging the material elevated by said conveyers upon the respective sides of the vessel.

3. In a marine vessel of the class described the combination of two parallel compartments located upon the respective sides of the longitudinal center of the vessel having parallel converging floors, discharge-apertures located at the apex of said floors, sliding doors for closing said apertures, a con-

veyer-belt located longitudinally beneath the discharge-passages of each compartment, a plurality of sets of belt-supporting rollers revolubly supported from the vessel beneath the upper and lower folds of said belt, the sets of rollers supporting the upper fold of said belt being arranged at an angle to each other so as to retain the upper fold resting thereon in a trough-shaped position while the sets of rollers supporting the lower fold are arranged in a horizontal position, a third conveyer located centrally between and extending upwardly at an angle to said first-named conveyers, a plurality of sets of rollers for supporting said third conveyer, two transversely-arranged conveyers communicating from said first-named conveyers and adapted to discharge their contents upon said central conveyer, a set of rollers for supporting said transverse conveyers, means for simultaneously operating all of said conveyers and means for discharging the material elevated by said conveyers upon the respective sides of the vessel.

In testimony whereof I affix my signature in the presence of two witnesses.
